A. L. Fleury

UNITED STATES PATENT OFFICE.

A. L. FLEURY, OF BALTIMORE, MARYLAND.

LAMP.

Specification of Letters Patent No. 24,622, dated July 5, 1859.

To all whom it may concern:

Be it known that I, A. L. FLEURY, of the city of Baltimore and State of Maryland, have invented a new and useful Improvement 5 in Fuel-Lamps; and I do hereby declare that the following is a full and clear description thereof, reference being had to the accompanying drawings, made to form a part of this specification.

10 My invention relates to certain improvements in device for burning coal and other oils by means of which intense heat may be produced, without the generation of smoke, as hereinafter described.

15 By reference to the accompanying drawings Figure 1 is an external view of the lamp, a portion of the chimney being removed, in order to exhibit the arrangement of parts at the point of combustion. Fig. 20 2, is a vertical sectional elevation of the lamp, showing the internal arrangement of its parts, together with device for adjusting the button. The cap shown in Fig. 5 is represented as being adjusted for use in the 25 lamp shown by Figs. 1 and 2. Fig. 3, is a 30 sectional elevation of the lamp, to which the cap shown in Fig. 4 is adjusted for producing more rapid combustion and more intense heat than can be secured by the use of the cap shown in Fig. 5.

(A) is the shell or body of the lamp and is a cylinder of suitable metal, attached to and supported by a perforated base (S) and provided with a cone shaped flue or tube 35 (A') which extends from the base (S) to the point of combustion, a little above the top of the cylinder (A) and is designed to supply oxygen to the inner portion of the flame. Surrounding this flue (A') and extending from its bottom to its top is a conoidal cylinder of quick lime (c) around which the wick (g) is wrapped. Surrounding the wick (g) and extending from near the base 40 of the lamp (leaving sufficient room for the admission of fluid to the wick) to near the upper part of the wick (sufficient space being left at the top to expose the wick thereby securing full supply of oil) is another 45 cylinder (c') of quick lime. The interpolation of the lime cylinders between the wick and the metals is intended to prevent the 50 carbonization of the wick, and thereby pre-

serve its full capillary conductive capacity. They are also intended to a certain extent to absorb the carbonic acid from the oils 55 and also from the combustion, as it forms and sinks into the oil receptacle. The flanged cylinder (k) is introduced to prevent splashing of the contained liquid by motion of the lamp. The perforations 60 (m') of the cap (a) are formed to allow a portion of the oxygen received through the perforations (a) of the lamp shell (A) to pass up around the flame without being forced directly into it. This cap should be 65 used when only a moderate heat is required.

The cap (n), Fig. 4, is formed with a short perforated cylinder (n') and extending flange (n'') and is intended to confine the oxygen, as supplied from the atmosphere, through the perforations (a) to a direct contact with the upper part of the wick, so as to produce the most rapid combustion. This cap (n) may be used when great heat 70 is required.

75 The height of the flame may be regulated by the button (d) which is adjustable by means of rod (e), lever (l) and stop (p).

The lamp may be supplied with oil by means of the tube (j), which is connected with the lower part of the lamp, and extends sufficiently high to keep the fluid, by hydrostatic pressure, always at the same height in the oil receptacle. This tube (j) is provided with a stop-cock (r) so that the 80 supply may be shut off when required.

(B) is a chimney, and may be formed of metal or earthen substance and is intended to be used when great focal heat is desired.

What I claim as my invention and desire to secure by Letters Patent is—

1. The quick lime cones (c, c') or their equivalents, arranged substantially as herein described, for the purposes set forth.

2. In combination with the above I claim 95 the flanged cap (n n' n'') substantially as herein described.

In testimony of which invention I have hereunto set my hand.

A. L. FLEURY.
